UNITED STATES PATENT OFFICE

MICHAEL J. DI GIACOMO, OF WILMINGTON, DELAWARE

PAPER HANGING MACHINE

Application filed March 14, 1929. Serial No. 346,895.

The invention relates to paper hanging machines and has as an object the provision of a device provided with means to apply paste to paper as it is unrolled and laid upon a wall 5 and also provided with means for cutting off the paper at the end of a strip.

It is a further object of the invention to provide a machine of this character having a brush for smoothing the paper upon the 10 wall, which brush is movably mounted to adapt the same to follow warped surfaces.

It is a further object of the invention to provide a machine of this character having a knife adapted to be caused to travel across 15 the width of the paper to cut the same at the end of a strip.

It is a further object of the invention to provide a machine wherein said knife may be placed to cut a strip of paper longitudinally 20 as the same is applied to the wall.

Further objects of the invention will appear from the following description when read in connection with the accompanying drawings showing an illustrative embodiment of the invention and wherein:

Fig. 1 is a side elevation of the device; 25
Fig. 2 is a detail perspective view of a portion of a knife driving belt;

Fig. 3 is a front elevation upon an enlarged 30 scale showing the handle broken away;

Fig. 4 is an end view;

Fig. 5 is a rear elevation corresponding to 35 Fig. 3;

Fig. 6 is a vertical transverse section on line 6—6 of Fig. 5; and

Fig. 7 is a detail vertical section partly in 40 elevation upon line 7—7 of Fig. 5 and upon an enlarged scale.

As shown the device comprises a handle 45 terminating in a socket 11 in which may be inserted extension handle 12 for manipulation of the device.

To support the roll of paper which is to be applied to a wall, there is a cylinder 13 rigidly secured transversely to a central bar member 14 forming a continuation of the handle 10. The bar 14 is shown as ending in a socket member 15 into which the handle member 10 may be inserted as by screw-threaded engagement.

To keep the roll of paper from sliding lengthwise in the cylinder 13, there are shown disks 16, 17 supported upon screws 18, 19, which screws have threaded engagement with perforated lugs 20, 21. Lock nuts 22, 23 are 55 shown to hold the screws 18, 19 in adjusted position and lock nuts 24, 25 to hold the disks 16, 17 in position opposite the ends of the cylinder. The cylinder 13 is shown as provided with a slot 26 (see Fig. 6) through 60 which the paper is led to be applied to the wall.

To apply paste to the paper as it is drawn from the roll, there is shown a spray head 27 supported by bars 28, 29 projecting from the 65 wall of the cylinder 13. It will be understood that the spray head 27 is provided with perforations facing the paper 30 and past which perforations the paper is led from the roll of paper 31.

To supply paste to the spray head 27, there is shown a pipe 32, which may be a flexible pipe as rubber, having one end slipped over a connection 33 as of metal supported upon a lug 34 carried by the rod 14. The connection 33 is shown as provided with a control valve 35 whereby the flow of paste to the spray head may be controlled, and, as shown in Fig. 1, a second pipe 36 leads from the connection 33 to a second connection 37 similar to the connection 33 and also bearing a control valve, 38. From the connection 37 there is shown a flexible pipe 39 leading to a reservoir 40 in which a supply of paste under pressure is provided, the pressure in which reservoir may be supplied as by an airpump 41. Desirably a third control valve 42 is provided to control the exit from the reservoir.

To press the paper against the wall and to smooth the same as it is applied, there is shown a brush 43 mounted upon a brush-head 44, which head is pivotally mounted upon the upper end of rod 14 upon the axis 45, and to retain the brush head resiliently in central position, there are shown springs 46, 47 anchored respectively to eyes 48, 49 carried by the brush-head and at their remaining ends to eyes 50, 51 carried by rod 100

14 thus enabling the brush to swing to follow warped surfaces.

To cut paper at the end of a strip as for instance at the edge of a baseboard after a strip of paper beginning at the ceiling corner of a side wall has been applied by the device, there is shown a knife in the form of a revoluble disk 52 mounted upon the slotted end of a shaft 53 and telescopically carried by a cylindrical socket 54 mounted upon a carriage 55. To enable the cutting disk to follow irregularities of the wall, the same is slidable in the socket 54 and retained therein as by means of a pin 56 passing through the shaft 53 and projecting into slots 57, 58 in the wall of the cylinder. To force the shaft outwardly in the cylinder, there is shown a spiral spring 59 acting in compression between the end of the shaft and the bottom of socket 54.

20 To enable the knife to be used either during travel, as already indicated, or to cut a strip of paper longitudinally, the socket 54 is mounted upon a disk 60 which is revoluble about the mounting screw 61.

25 To hold the disk 60 in its desired position, there are shown retaining members, as balls 62, 63 pressed upwardly to project through perforations in the lower disk 64 of the knife carriage as by means of spiral springs 65, 66 carried in sockets 67, 68, which sockets are secured to the disk 64.

30 In the use of the device when papering a surface without openings the knife will be adjusted upon the ways upon the curved portion 91 or 92 so as to be at one side or the other of the strip to be placed. Paste is applied to the end of the strip of paper which is then placed against the wall at one end of the space to which it is to be applied and the 35 control valves are opened to allow paste to be expelled through the spray head 27 when the brush is moved to apply the paper to the wall. At the end of the strip as when the baseboard is reached, the control valve is 40 closed and the crank 90 is revolved having the cutter 52 in the position shown in Figs. 5, 6, and 7 thus causing the cutter to move across the strip of paper to cut the same, after 45 which the process may be repeated with the next strip.

50 If paper is to be applied adjacent a wall opening when only a portion of a width is needed, the full width of the paper may be applied above the opening in the manner already described for a full width strip, the 55 knife may be caused to travel to cut off the paper above the opening and may be carried to a position opposite the vertical side of the opening and by pulling on the appropriate wire 69 or 70 the knife may be turned to the 60 position shown in Fig. 1, whereupon as the device is moved downwardly the knife will automatically cut the paper during its application.

To revolve the disk 60 upon the disk 64, there are shown a pair of flexible members, as wires 69, 70 extending from a position alongside the handle 10 through guide tubes 71, 72 and through ears 73, 74 carried by a flange 75 projecting from the socket 54, the 70 ends of the wires being secured to the flange as at 76, see Fig. 6. It will be seen that by pulling upon the appropriate member 69 or 70, the socket 54 may be revolved through an arc of 90° to place the knife into the desired position.

To mount the knife movably, the disk 64 is shown as provided with lugs 77, 78, which engage about ways 79, 80 and to cause the knife to incline toward the brush in the position shown in Figs. 1 and 6 a spacing lug 81 is shown opposing the lug 77 and contacting with the opposite side of way 79.

To cause travel of the thus described carriage upon the ways 79, 80, there is shown a belt 82 which is desirably of the character indicated in Fig. 2, said belt is shown as attached to the carriage by grip members 83, 84, shown in detail in Fig. 7, and the belt which is endless about idle pulleys 85, 86, 87, 88 and about a drive sheave 89 which may be revolved as by means of a crank 90 to drive the belt and thus cause travel of the knife.

95 When using the device upon a side wall the upper portion of which is out of reach of the operator, the valve 38 may be closed and the valve 35 may be opened before beginning the application of the paper and the control of the paste will then be possible by use of valve 38 which is within the reach of the operator manipulating the device by using the extension handle 12. When the bottom of the strip is approached by the valves 35 and 38 being opened, the flow of paste may be cut off by using valve 35 after which valve 38 may be closed preparatory to opening valve 35 for repetition of the process.

100 It will be observed that the paper roll carrier is essentially a guide to direct paper to a position to be applied and an equivalent would be a slot through which paper is passed with the supply roll lying on the floor at the foot of the wall.

105 Minor changes may be made in the physical embodiment of the invention within the scope of the appended claims without departing from the spirit thereof.

I claim:

110 1. A paper hanging machine comprising, in combination, a supporting member, a paper supply roll carrier mounted on said member, means pivotally mounted on said member on an axis normal to the plane of the paper to press paper against a surface, said means yieldable about said pivot to follow irregularities of the surface and means to apply adhesive to the paper as it leaves the supply roll.

2. A paper hanging machine comprising, in combination, a supporting member, a paper supply roll carrier mounted on said member, means pivotally mounted on said member on an axis normal to the plane of the paper to press paper against a surface, said means yieldable about said pivot to follow irregularities of the surface, resilient means to hold said means normally in a central position and means to apply adhesive to the paper as it leaves the supply roll. 5
3. A paper hanging machine comprising, in combination, a supporting member, a paper supply roll carrier mounted on said member, means pivotally mounted on said member to press paper against a surface, a pair of tension resilient members anchored to said member and to said means one at each side of its pivot to yieldingly hold said means in central position and means to apply adhesive to the paper as it feeds from the supply roll. 10
4. A paper hanging machine comprising, in combination, a supporting member, means carried by said member to press paper against a surface, means to guide a supply of paper into position to be applied, means carried by said member to movably mount cutting means for severing applied paper, a cutting edge carried by said mounting means, said cutting edge rotatable to a position to cut paper during movement of said mounting or to a position to cut paper during movement of said pressing means, the width of paper severed by said last named use dependent upon the position of the cutting edge determined by adjustment of said movable mount. 15
5. A paper hanging machine comprising, in combination, a supporting member, a bar pivotally mounted transversely upon said member, resilient means to hold said bar yieldingly in position perpendicular to said member, a paper pressing element carried by said bar, means to guide a supply of paper to position to be applied by said element, ways mounted on said bar, a carriage mounted to travel on said ways longitudinally of said bar, and a cutting edge supported on said carriage to sever applied paper from the supply during travel of said carriage. 20
6. A paper hanging machine comprising, in combination, a supporting member, a bar pivotally mounted transversely upon said member, resilient means to hold said bar yieldingly in position perpendicular to said member, a paper pressing element carried by said bar, means to guide a supply of paper to position to be applied by said element, ways mounted on said bar, a carriage mounted to travel on said ways longitudinally of said bar, a cutting edge supported on said carriage to sever applied paper from the supply during travel of said carriage, and a flexible member secured to said carriage operable to cause travel thereof. 25
7. A paper hanging machine comprising, in combination, means to press paper against a surface, ways mounted on said means, a carriage movable on said ways transversely of the strip of paper applied thereby, a cutting member mounted on said carriage for severing applied paper, a drum movable with said means, an endless belt secured to said carriage and passing about said drum for causing travel of the carriage and cutting member along said ways. 30
8. A paper hanging machine comprising, in combination, a supporting member, paper applying means mounted on said member, means carried by said member to guide a supply of paper to position to be applied, a spray head carried by said member, a source of liquid adhesive under pressure in communication with said spray head and means to control flow of adhesive to said head. 35
